UNITED STATES PATENT OFFICE.

FRANK SHAW, OF SYRACUSE, NEW YORK.

SHAFT-CO尤LING.

SPECIFICATION forming part of Letters Patent No. 674,024, dated May 14, 1901.

Application filed April 6, 1896. Serial No. 586,354. (No model.)

To all whom it may concern:

Be it known that I, FRANK SHAW, of Syracuse, in the county of Onondaga, in the State of New York, have invented new and useful 5 Improvements in Shaft-Couplings, of which the following, taken in connection with the accompanying drawings, is a full, clear, and exact description.

My invention relates to improvements in 10 shaft-couplings of the class set forth in my previous patent, No. 441,445, of November 25, 1890, and in my divisional application, Serial No. 33,638, filed October 19, 1900, and has for 15 its object the production of a device which is cheaply manufactured and is particularly effective and durable in use; and to this end it consists, essentially, in the combination, construction, and arrangement of the outer shell and the inner sleeve of the shaft-coupling, as hereinafter fully described, and pointed out in the claims.

In describing this invention reference is had to the accompanying drawings, forming 20 part of this specification, in which like letters indicate corresponding parts in all the views.

Figure 1 is a longitudinal vertical sectional view of my improved shaft-coupling, its inner sleeve being shown in elevation and as 25 operatively engaged with a shaft. Fig. 2 is an end view of a portion of my improved shaft-coupling. Figs. 3 and 4 are transverse and longitudinal sectional views taken, respectively, on lines 3 3 and 4 4, Figs. 1 and 3, the shaft being omitted in Fig. 4. Fig. 5 is 30 a plan view of the inner sleeve of my shaft-coupling shown as split lengthwise and as folded flat.

A A are movable sections forming the outer shell of my improved shaft-coupling, and C 40 is a shaft-receiving sleeve arranged within said shell. The sections A A are formed with conical or tapering inner faces a and apertures a' and are adjusted or drawn toward each other by clamping means, as bolts D. 45 The inner sleeve C encircles the divisions of the shaft D' to be coupled, is composed of spring metal, and is formed with conical or tapering ends, which engage the inner faces a of the sections A A. The inner face of the 50 sleeve C is normally of slightly less diameter than the divisions of the shaft D' to be coupled. Said sleeve C is formed with a plural-

ity of longitudinal substantially equidistant slots c, extending from one of its end faces into proximity to the opposite end face, and with 55 a plurality of additional substantially equidistant longitudinal slots c', extending alternately between the slots c from said opposite end face into proximity to the former end face. The slots c divide the sleeve C into a 60 number of yielding parts c², which taper or decrease in thickness toward the ends of the sleeve, are formed with substantially concave inner faces, are connected together at opposite sides at one end of the sleeve, are separable 65 at opposite sides from their connected portions to the opposite end of the sleeve, and engage the faces a of the sections A A and the periphery of the shaft D', inserted within said sleeve, and each slot c' extends from substantially the central point of the end edge of the connected end of one of the yielding parts c² and divides said yielding part into longitudinal yielding divisions or branches 70 connected together at the free end of said 75 yielding part and separable from their connected portions to the opposite end of the sleeve.

The described construction of the sleeve C is particularly efficient, since portions of the 80 parts c² and their divisions or branches are connected together at the ends of the sleeve and additional portions of said parts and their divisions or branches are separable from each other owing to the presence of the slots 85 c c', thus permitting the sleeve C, having its inner face normally of less diameter than the shaft D', to be expanded to encircle said shaft without change in the curvature of the inner faces of said movable parts c² and their 90 divisions or branches, whereupon the lengthwise edges of the inner faces of said parts and their divisions or branches will rest upon the shaft D', and the interposed portions of said inner faces will be slightly separated 95 from the contiguous portion of the periphery of the shaft D', and as the sections A A are drawn together by the bolts D said parts c² and their divisions or branches will firmly and positively hold the shaft D'. 100

The construction and operation of my shaft-coupling will now be readily perceived upon reference to the foregoing description and the accompanying drawings.

Having thus fully described my invention, what I claim as new, and desire to secure by Letters Patent, is—

1. In a shaft-coupling, the combination with an outer shell consisting of sections having tapering inner faces, and clamping means for adjusting the sections endwise toward each other; of a shaft, and a sleeve for encircling the shaft, said sleeve being arranged within the outer shell and having its inner face normally of less diameter than said shaft to be encircled thereby, and being provided with substantially longitudinal movable parts for engaging said tapering inner faces and the periphery of the shaft, said substantially longitudinal movable parts having substantially concave inner faces and having portions thereof connected and additional portions thereof separable from each other for permitting the sleeve to be expanded to encircle the shaft without change in the curvature of the inner faces of said movable parts, substantially as and for the purpose described.
2. In a shaft-coupling, the combination with an outer shell consisting of sections having tapering inner faces, and clamping means for adjusting the sections endwise toward each other; of a shaft, and a sleeve for encircling the shaft, said sleeve being arranged within the outer shell and having its inner face normally of less diameter than said shaft to be encircled thereby, and said sleeve being formed with

longitudinal substantially equidistant slots extending from one end face into proximity to the opposite end face, and thereby forming a plurality of longitudinal yielding parts connected together at one end of the sleeve, and having substantially concave inner faces and being also formed with additional slots extending alternately between the former slots from said opposite end face of the sleeve into proximity to the former end face of the sleeve for dividing said yielding parts into yielding divisions or branches, the divisions or branches of each yielding part being connected at the free end of said part, and said parts and their divisions or branches having their portions on opposite sides of said slots separable from each other for permitting the sleeve to be expanded to encircle the shaft without change in the curvature of the inner faces of said movable parts and their divisions or branches, substantially as and for the purpose set forth.

In testimony whereof I have hereunto signed my name, in the presence of two attesting witnesses, at Syracuse, in the county of Onondaga, in the State of New York, this 18th day of March, 1896.

FRANK SHAW.
